L. S. GORDON

RADIO LOUD SPEAKER

Filed July 21, 1926

FIG. 1

FIG. 2

Inventor:
Leslie S. Gordon
By G. K. Gruzz Atty.

Patented Dec. 28, 1926.

Des. 71,756

UNITED STATES PATENT OFFICE.

LESLIE S. GORDON, OF WINNETKA, ILLINOIS, ASSIGNOR TO H. G. SAAL COMPANY, OF CHICAGO, ILLINOIS, A CORPORATION OF ILLINOIS.

DESIGN FOR A RADIO LOUD SPEAKER.

Application filed July 21, 1926. Serial No. 18,438. Term of patent 3½ years.

To all whom it may concern:

Be it known that I, LESLIE S. GORDON, a citizen of the United States, residing at Winnetka, in the county of Cook and State of Illinois, have invented a new, original, and ornamental Design for Radio Loud Speaker, of which the following is a specification, reference being had to the accompanying drawing, forming part thereof.

In the drawing Fig. 1 is a front view of a radio loud speaker showing the design of my invention and Fig. 2 is a side view of the loud speaker shown in Fig. 1.

I claim:

The ornamental design for a radio loud speaker, as shown.

LESLIE S. GORDON.
